FRANK J. LIESKE, OF DETROIT, MICHIGAN, ASSIGNOR, BY MESNE ASSIGNMENTS, OF ONE-HALF TO AMERICAN ENGINEERING ASSOCIATES, A TRUST ESTATE OF MICHIGAN.

SUBMARINE.

1,300,745.

Specification of Letters Patent. Patented Apr. 15, 1919.

Application filed October 2, 1918. Serial No. 256,499.

To all whom it may concern:

Be it known that I, FRANK J. LIESKE, a citizen of the United States, residing at Detroit, county of Wayne, State of Michigan, have invented a certain new and useful Improvement in Submarines, and declare the following to be a full, clear, and exact description of the same, such as will enable others skilled in the art to which it pertains to make and use the same, reference being had to the accompanying drawings, which form a part of this specification.

This invention relates to submarines, and its object is to provide a main submarine adapted to receive an auxiliary submarine at the rear end thereof and at the rear of the conning tower, the auxiliary being a complete submarine on a small scale adapted to be moved by its own power into interlocking relationship with the main submarine in each instance and providing compartments when in position on the main submarine which may be entered freely at all normal times, means being provided to close the passageway between the main and auxiliary submarines, both on the main and auxiliary submarine whereby the auxiliary may be withdrawn without detriment to the main submarine and also providing a means of escape for occupants of the main submarine in case of accident thereto. The principal features of this invention, as distinguished from my pending application, Serial No. 176,465, is in the provision for means on the deck of the main submarine at the back of the conning tower whereby loss of space in the main submarine is avoided and further by placing the auxiliary back of the conning tower, the resistance to movement of the submarine is not materially increased. In case both auxiliary submarines are utilized, as is hereinafter described, the auxiliary submarine should be as nearly as possible complementary to the shape of the main submarine to reduce the resistance of movement to a minimum. Further features of the invention are involved in providing a slideable carrier in the auxiliary submarine carrying a torpedo, and the carrier adapted to close the passageway ordinary.

narily utilized to enter the main submarine, the carrier being open at the forward end allowing the torpedo to be projected through the forward end of the passageway. A further novel feature of the invention is involved in the means for moving the auxiliary submarine into its final relationship with the main submarine. 55

An additional object is a main submarine or sea-going vessel provided at the rear end 60 with vertical and horizontal propellers, the horizontal propeller in addition to the main propeller being positioned transversely of the body of the vessel whereby the rear end thereof may be swung to the right or left 65 and to steady the main submarine to allow the auxiliary to be moved thereinto. An additional object is a submarine provided with an inner and outer hull with partitioned members extending therebetween longitudinally of the vessel providing water tanks and tending to hold the vessel on an even keel. These and other novel features of the invention are hereinafter more fully described and claimed and shown in the accompanying drawings in which— 70 75

Figure 1 is an elevation of a submarine embodying my invention.

Fig. 2 is a longitudinal vertical section thereof. 80

Fig. 3 is an elevation of an auxiliary submarine.

Fig. 4 is a longitudinal section thereof showing the means for closing the passageway and the carrier for the torpedo also 85 adapted to close the passageway.

Fig. 5 is an elevation of the stern of the auxiliary submarine.

Fig. 6 is a perspective view of the means employed to lock the auxiliary to the main 90 submarine.

Fig. 7 is a view of a portion of the auxiliary and main submarine showing the means of locking the auxiliary submarine from vertical movement relative to the main submarine. 95

Fig. 8 is a cross section on an enlarged scale taken on line A—A of Fig. 1.

Fig. 9 is a cross section on a different scale taken on line B—B of Fig. 1. 100

Fig. 10 is a vertical section of the rear end of an ordinary vessel showing my auxiliary submarine in conjunction therewith.

Fig. 11 is a cross section taken on line 5 $z-z$ of Fig. 10.

The drawings are practically diagrammatic in form showing only the general relationship of the several elements described, and not attempting to show the exact mechanical detail as, for instance, the hull wall or sides or the general operating device, being here merely indicated to make clear the invention described. The main submarine shown in Fig. 1 may be of any general type provided with the usual periscope 1 and the conning tower 2, giving access to the main submarine. This main submarine is provided at the forward end with torpedo tubes 3 and 7 and provided with torpedoes in the usual manner which are discharged by the usual well known mechanism not here shown. It is also to be understood that the boat may be operated by any well known motive power, for instance an internal combustion engine indicated at 4, which propels the boat and operates the electrical generator 5. Also tanks 6 are provided at points within the hull of the main submarine adapted to be filled with water for submerging or expelling to cause the submarine to rise. As in my former application, the main submarine may be provided with a slip 11 open at the rear end and upper side thereof to receive an auxiliary submarine 8. This auxiliary is provided at the forward end with a tube 9 which may be used as an entrance to the auxiliary submarine and made to fit tightly an aperture 10 at the forward end of the said slip in the wall of the main submarine when in place. This tube forms part of the passageway between the two vessels and is adapted to be closed by a torpedo tube 30 which carries the torpedo 31 therewithin and has an open forward end adapted to be inserted in the tube 9 of the auxiliary submarine in a manner to close the opening so that previous to disengagement of the two vessels the torpedo tube may be moved into the tube 9 closing the same and positioning the tube for discharge in the usual manner after withdrawal of the auxiliary. Preferably, this tube is arranged to ride on ways 32 in the upper surface of the interior of the auxiliary submarine by means of complementary ways 33, and the tube 30 may thus be moved longitudinally thereof as may be desired. The tube 9 may also be closed by the door device indicated at 28 operable from the interior of the auxiliary and the aperture 10 of the main submarine may be closed previous to the disengagement of the two submarines by means of the cylindrical block 12 which is adapted to be moved longitudinally on ways 13 and forced into the

opening and preferably locked in position therein to prevent leakage through the aperture 10 upon withdrawal of the auxiliary. The block is supported at the rear end by means of a shaft 14 carried in supports 14 riding in the ways 13. The auxiliary is also provided with a motor 34 and propeller 35 operated thereby and is also provided with water tight portlights 29 and usual submerging tanks and appurtenances of the larger device (not here shown). In all the general features the auxiliary submarine is a miniature of the main submarine and it is to be understood that the auxiliary is adapted to fit tightly in the slip 11 of the submarine and the tube 9 fitting the aperture 10 and the joint between the main and auxiliary submarines provided with a gasket 43 and a recessed end 44 shown in Fig. 3 adapted to engage against shoulders formed by a portion engaged thereby on the main submarine. When the auxiliary submarine is in place on the main submarine, the block 12 may be withdrawn and the door member 28 or tube 30 in the auxiliary may also be withdrawn, giving free access from one to the other.

The auxiliary submarine provides a separate compartment of the main submarine and, as will be understood from the above, the auxiliary submarine is operable by its own power and is to be movable into the slip to a partial extent, at least by its own power. Upon movement of the auxiliary, practically the entire extent, it may be drawn forward to locked position in the slip 11 by means of mechanism provided in the auxiliary submarine which consists of a motor 17 adapted to drive the shaft 18 by means of the belt 19 and thus turning the gear 20 which is in mesh with the gear 21 threaded on the shaft 22 of the engaging member 15. This member 15 ordinarily protrudes as shown by dotted lines in Fig. 3 and engages over the hook member 16 provided at the forward end of the slip on the main submarine. By threading the gear on the shaft 22 of the hook member, rotation of the gear causes longitudinal movement of the shaft 22 and member 15. As the gear is turned the auxiliary submarine is drawn forward until the tubular nose 9 engages tightly in the aperture therefor in the main submarine as is described in my said pending application. It is to be understood that the block 12, when the auxiliary is out of position, fills the aperture 10 and maintains it closed until the auxiliary has been again brought to final position, the construction being such as to allow this operation, and when the auxiliary has been brought to final position, the block 12 may be withdrawn from the inside of the main submarine.

To prevent rotation of the shaft 22 and

prevent the member 15 from turning with the gear 21, a squared end 60 is provided thereon as shown in Fig. 6 fitting a squared aperture 47 at the rear end of the shaft 5 housing. As shown more particularly in Fig. 3, the auxiliary submarine is provided with a flange 23 on opposite sides having undercut lugs 24. The main submarine at the upper edge of the slip 11 and on opposite sides 10 is provided with lugs 25 thereon having hooked ends adapted to engage over the inner ends of the lugs 24, and these parts are brought to locking relation by longitudinal movement of the auxiliary submarine in the slip. As is shown in Fig. 3 the keel of the auxiliary is provided with lugs 26 thereon adapted to engage beneath similar lugs 27 provided in the bottom of the slip on the main submarine. As will be 15 understood from the above, as the auxiliary moves to position in the slip and settles thereinto, the undercut lugs 24 are introduced between the lugs 25 on the main submarine and similarly the lugs 26 engage between the lugs 27. Upon the auxiliary submarine being moved forward the several lugs are brought to interlocking relation, preventing vertical movement of the auxiliary when in the slip. Longitudinal 20 movement of the auxiliary is prevented by the locking members 15 and 16.

It is to be understood that the auxiliary 8 moves into the slip 11 substantially in the same manner as a ferry boat moves into its slip. The main submarine may be moved about to receive the auxiliary submarine by means of the propellers 40 and 41 before mentioned.

I have shown the auxiliary as applied to 40 a submarine vessel. It also may be used in connection with a sea-going vessel of other character as a warship, passenger or freight boat in connection with which a submarine may be found useful. The construction of 45 the auxiliary and slip for this type of vessel is practically identical with that used for a main submarine except that as shown in Fig. 10 a slightly different locking means is employed. The shaft 22^a has a gear 21^a 50 keyed thereon and rotation of the gear 20 thus rotates the shaft 22^a and threaded head 45 thereon which is adapted to be inserted in a threaded socket 46 at the forward end of the slip. Rotation of the shaft in one direction therefore draws the auxiliary forward and reverse rotation tends to move it 55 backward in the slip.

As will be understood from Figs. 1, 2 and 9, a second slip 111 may be provided with 60 the same character of locking device and lugs as the slip 11 in the body of the vessel. This slip 111, however, should be no greater in width than the conning tower so that forward movement of the vessel is not restricted by this construction. This second

auxiliary is in all general respects the same as the auxiliary above described except as to the positioning. By this arrangement the usual submarine having a conning tower may be readily remodeled to accommodate 70 an auxiliary by building a receiving slip on the deck or surface of the main submarine and providing an opening in the conning tower similar in all respects to that above described for introduction of the tube 75 9 at the forward end of the auxiliary thereinto. Preferably, the conning tower is elongated at the back as indicated at 56 to provide the desired forward end of the slip 80 conforming to that described in the forward 85 end of the slip 11 in the rear end of the vessel. By thus providing an auxiliary submarine at the rear of the conning tower, one object of the invention is attained and a comparatively inexpensive construction 90 secured whereby a submarine may be remodeled to utilize an auxiliary and further to position an auxiliary in such a manner to present little resistance to forward movement of the main submarine. The slip is 95 ordinarily of a width not greater than the width of the conning tower but, if it be desired or necessary to make the slip greater in width than the width of the conning tower, this may be accomplished by increasing 100 the length of the wedge shaped portion 36 at the forward side of the conning tower as indicated particularly in Figs. 1 and 2. By use of such wedge shaped portion the conning tower and slip may present the least 105 resistance to forward movement of the vessel in the water. To assist in operation of the vessel when at or near the surface this wedge shaped portion may be provided with a sight device illustrated diagrammatically 110 at 37 and also a similar device indicated at 38 positioned at the prow of the vessel. These sight devices or tubes may be of any preferred construction to enable the crew to make an observation from within the interior of the vessel and may be utilized in addition to the usual periscope 1.

As heretofore stated, the auxiliary may be used with other sea-going types of vessels in which case the bottom of the slip formed in 115 the rear end thereof as indicated in Fig. 10 should be at or below the water level. By means of the vertical and transversely positioned propellers 40 and 41 the rear end of the vessel may be depressed or moved in a 120 horizontal plane sufficiently to allow the forward end of the auxiliary to be introduced into the slip 11. These propellers are to be understood as being connected with the motive power in order to permit operation 125 thereof when desired. To assist in moving the auxiliary submarine forward into the slip, I have provided a rack 48 formed in the lower edge of the keel carrying the lugs 26. This rack is adapted to engage a gear 130

49 positioned with the upper face thereof extending slightly above the floor of the slip and inclosed by a housing 52 to prevent water from flowing into the vessel. Upon 5 movement of the auxiliary into the slip sufficiently to engage the rack into the gear the shaft 50 of the gear which extends into a compartment in the main vessel may be rotated by means of the hand wheels 51 or 10 by means of a power if so desired, as by a chain on these wheels 51, and rotation thereof causes movement of the auxiliary to position. Reverse rotation would back the auxiliary out of the slip and when the propeller thereof is submerged, the power may 15 be applied by the motor 34 to withdraw the same. Preferably, I provide the main submarines with keels 42 disposed on opposite sides of the base of the submarine to stabilize it when on the bed of the ocean. The main submarine is also provided with an interior shell 54 as indicated in Fig. 9 or two shells as shown at 54 and 55 in Fig. 8. Between these shells and the outer shell 53 20 suitable water tanks 66 may be provided by longitudinal partition members 67 extending from one shell to the other transversely. This arrangement of partitions strengthens the device and further provides water spaces 25 in which the water may not roll transversely from one side of the boat to the other causing an unstable condition.

The described features of this invention provide one or more life boats utilizable 35 with the usual type of submarine and enabling the occupants of the main vessel to escape in case of disablement of the main submarine from any cause. By the construction described and shown the life boat 40 of the auxiliary back of the conning tower is provided, having all the features described relative to the auxiliary submarine and utilizable therewith without encroaching upon the limited space within the main submarine. Further, by providing a torpedo tube in the auxiliary adapted to close 45 the passageway in the auxiliary, a means of defense is provided in the auxiliary which also locks the entrance thereto automatically 50 in the positioning of the tube. The entrance between the auxiliary and the main submarine, when in position, should be at all times maintained open so that in case of accident ready access may be had thereto, and if a 55 destructive accident happens to the main submarine, the crew may pass into the auxiliary submarine and close the opening in the auxiliary and return to the surface by means of the auxiliary. In ordinary cases, 60 however, where the auxiliary is used as a supplemental vessel and part of the crew remaining in the main submarine, the entrance in the main submarine should be closed prior to disengagement of the auxiliary.

65 The utility of providing a submarine or

other vessel is believed sufficiently evident as the auxiliary may be used in all ways as a motor boat in running to and from a land station to a submerged main submarine or to perform various requirements as it is 70 more readily operated than the main submarine and can be operated in shallow water or in channels or the like difficult of approach by a submarine of large size. The auxiliary on sea-going vessels of any type is 75 obviously more for the purpose of defense against a submarine attack and in case of sinking the main vessel may be used as a life boat.

Having thus fully described my invention, 80 what I claim is—

1. In a device of the character described, a main submarine provided with a conning tower projecting above the upper surface thereof, a pair of auxiliary submarines individually operable by their own power, a receiving slip formed in the rear end of the main submarine below the upper surface thereof, a second receiving slip provided on the upper surface of the main submarine at 85 the rear of the conning tower, said conning tower having an extension forming the forward end of the said slip, the forward end of both slips being provided with an aperture and the auxiliary submarine when in 90 position in the slip having an opening registering with the said aperture.

2. In a device of the character described, a main submarine having a conning tower, a pair of auxiliary submarines each operable by its own power, a receiving slip for 100 an auxiliary formed at the rear end of the main submarine, a receiving slip formed at the rear of the conning tower, the width of which is not greater than the width of the 105 conning tower, and complemental means at the forward end of each slip and auxiliary providing a means of communication between the main and auxiliary submarines when positioned in the respective slips.

3. In a device of the character described, a main submarine provided with a conning tower projecting above the upper surface, a receiving slip formed at the rear of the conning tower, a second receiving slip formed 115 in the rear end of the submarine, the first slip terminating short of the said second slip whereby the submarine in the second slip may float vertically out of position when the first slip is occupied, an auxiliary 120 submarine for each slip operable by its own power, and complemental means at the forward end of each slip and auxiliary submarine respectively coöperating to provide a passageway between the main submarine 125 and each auxiliary respectively when finally positioned in the respective slip.

4. In a device of the character described, a main submarine provided with a conning tower extending above the upper surface 130

- thereof, a receiving slip provided on the surface of the submarine at the rear of the conning tower, the slip being open at the rear end and upper side and being of a width not 5 greater than the width of the conning tower, said conning tower at the rear side having an extension providing a vertical wall forming the forward end of the slip and having an aperture, an auxiliary submarine oper- 10 able by its own power adapted to be moved into the slip, means for securing the auxiliary submarine therein, and means of communication between the interiors of the auxiliary and main submarine through the con- 15 ning tower.
5. In a device of the character described, a main submarine provided with a conning tower extending above the upper surface thereof, a receiving slip provided on the sur- 20 face of the submarine at the rear of the conning tower, the slip being open at the rear end and upper side and being of a width not greater than the width of the conning tower, said conning tower at the rear side 25 having an extension providing a vertical wall forming the forward end of the slip, an auxiliary submarine operable by its own power adapted to be moved into the slip, means for securing the auxiliary and main 30 submarine in interlocking relation, an aperture provided in the said vertical wall of the conning tower extension, a tubular pro- 35 jection on the forward end of the auxiliary adapted for insertion thereinto and means for sealing the interstice between the aperture and tubular projection of the auxiliary, means for closing the aperture from within the conning tower, a tubular member movable longitudinally of the auxiliary open at 40 the forward end only and adapted to be inserted in the said extension of the auxiliary in a manner to seal the same, said tubular member comprising a torpedo carrier from which a torpedo may be projected through 45 the open forward end.
6. In a device of the character described, a main submarine provided with a receiving slip, an auxiliary submarine operable by its own power and adapted to be moved into the 50 slip, an aperture provided at the forward end of the slip opening into the interior of the main submarine, a tubular extension on the forward end of the auxiliary adapted for engagement in said aperture and providing 55 means of access to the auxiliary from the main submarine, means for closing the aperture from the main submarine, a tubular member open at the forward end only adapted for insertion in the projecting tubu- 60 lar portion of the auxiliary in a manner to seal the same, the tubular member comprising a torpedo carrier from which a torpedo may be projected through the said opening.
7. In a device of the character described, 65 a sea-going vessel provided with a receiving slip at the rear end, the bottom of which is practically at about the water level and open at the rear end and upper side, an auxiliary submarine operable by its own power and adapted to be inserted to a partial extent 70 into the slip, a keel on the auxiliary having rack teeth on the lower edge thereof, a gear in the bottom of the slip extending thereinto and adapted to be engaged by the rack on partial introduction of the auxiliary into the 75 slip, means for operating the gear from within the main vessel to complete the movement of the auxiliary into the slip, and means providing access to the auxiliary from the interior of the main submarine. 80
8. In a device of the character described, a main submarine provided with a conning tower extending above the upper surface, a receiving slip formed at the rear of the conning tower, an auxiliary submarine for the 85 said slip operable by its own power and adapted to be moved thereinto, there being a passageway provided from the conning tower to the auxiliary when positioned in the slip, said slip being formed with walls 90 coextensive with the walls of the conning tower and being of a character in general outline to present least resistance to forward movement of the main submarine, and means for locking the auxiliary in place, said lock- 95 ing means being operable from the interior auxiliary.
9. In a device of the character described, a main submarine provided with a conning tower extending above the upper surface, a 100 receiving slip formed at the rear of the conning tower, the side walls of the conning tower converging at the forward side there- 105 of extending at an angle toward the rear terminating with the side walls respectively of the slip, an auxiliary submarine for the slip operable by its own power and adapted to move thereinto, and means for locking the auxiliary in place.
10. In a device of the character described, 110 a sea-going vessel provided with a receiving slip at the rear end the bottom of which is practically at the water level and open at the rear end and upper side, an auxiliary submarine operable by its own power 115 adapted to be inserted thereby to a partial extent into the slip, propelling devices for moving the main vessel in vertical or trans- 120 verse directions to position the same to receive the auxiliary, a keel on the auxiliary having rack teeth, a gear in the bottom of the slip near the rear end and extending thereinto engaged by the rack on partial introduction of the auxiliary, mechanism for operating the gear from within the vessel to 125 move the auxiliary forward into the slip, the forward vertical wall of the slip having an aperture, a tubular extension on the aux- 130 iliary adapted to engage therein on comple- tion of its movement into the slip and pro-

viding a passageway from the vessel into the auxiliary, and a locking device for moving the auxiliary to final position comprising a rotatable screw threaded member operable 5 from within the auxiliary and a threaded aperture in the forward vertical wall of the slip engaged thereby and lugs on the side

walls of the slip engaging complemental lugs on the auxiliary preventing vertical movement of the submarine in the slip when 10 in final position.

In testimony whereof, I sign this specification.

FRANK J. LIESKE.
